UNITED STATES PATENT OFFICE.

WILLIAM E. BENSON, OF WILMINGTON, MASSACHUSETTS, ASSIGNOR TO KALIX CUP COMPANY, OF BOSTON, MASSACHUSETTS, A CORPORATION OF MASSACHUSETTS.

PAPER DRINKING CUP.

Original application filed October 16, 1922, Serial No. 594,775. Divided and this application filed January 22, 1923. Serial No. 614,082.

This invention relates to waterproofed paper receptacles, and particularly to paper drinking cups of the type wherein the bottom closure is a separate piece sealed to the 5 wall of the cup.

My present invention is a division of my prior application, Serial No. 594,775, filed October 16, 1922, covering the method of and apparatus for producing my novel cup 10 claimed specifically herein.

One characteristic difficulty in the production of cups of this type in commercial quantities consists in the union of the bottom closure to the cup wall. This is of necessity 15 the area of greatest weakness in this type of cup, and is usually united by coating the contacting surfaces of the blank and closure with glue or paraffin and pressing them together to seal them.

One object of my present invention is to 20 provide a cup in which the contacting surfaces of these parts will be positively pressed together and worked relative to each other in such manner as to cause them to firmly 25 adhere to each other.

Another object of my invention is to provide a closure which will not open up when the cup is filled. As contemplated herein, the bottom flange of the cup wall is disposed 30 at substantially the same angle as the flaring cup wall itself but is reversed relative thereto. This leaves a space between the cup wall flange and the wall itself within which the flange of the bottom closure snugly seats, 35 and actually increases the pressure of the cup wall against the flange of said bottom closure after the cup wall and closure have been sealed together.

A further object of my invention is to 40 provide a cup which will instantly indicate whether or not it has been previously used. According to my invention, the cup wall may be made of transparent paper stock, thereby permitting the internal seam or overlap of 45 the cup to be viewed through the cup wall. Inasmuch as said seam will hold moisture, the prospective drinker can immediately detect whether or not the cup has been previously used. The use of transparent stock, 50 moreover, permits the contents of the cup, when filled to be viewed through the cup wall, and is a desirable feature in connection with certain types of cups, as for example, the soda fountain cups in which variously 55 colored drinks are served.

Another object of my invention is to provide a cup which may be nested in a manner best suited for dispensing from a dispensing machine. As contemplated herein, the cups will have inwardly rolled beads or rims at 60 their upper edges and such rims will prevent the cups from nesting too closely together by reason of the reduction in effective diameter of the cups at their upper edges. With the outwardly rolled bead or with the plain edge 65 cup, the cups nest snugly within each other with the bead of one resting upon the bead of the cup next below in the column, and hence frequently stick together and come out in groups when withdrawn from the dispens- 70 ing machine.

These objects and various other features of advantage which will appear more particularly hereinafter, are secured in the cup 75 of the present invention.

The construction of my cup is described and illustrated in the accompanying specification and drawings, throughout which like reference characters are employed to indicate corresponding parts, and the characteristic features of novelty are particularly 80 pointed out in the appended claims.

In the drawings:

Fig. 1 is a view of a paper drinking cup in accordance with my invention.

Fig. 2 is a vertical section thereof.

Fig. 3 is a view of the bottom closure, detached, and

Fig. 4 is a partial section particularly illustrating the angular relation of the cup 90 wall to the flange thereof.

In the type of cup selected herein as illustrative of the principles involved, the cup blank is dinked out of transparent paper stock, if desired, in an ordinary dinking or stamping press, glued along one vertical edge and then rolled upon a forming mandrel to lap its opposite vertical edge over said coated edge.

At this stage, the blank is formed to cup shape, as indicated at 1 in the drawings, but has not been bent at its bottom edge to provide the closure attaching flange 2 or rolled at its top edge to provide the inturned bead or rim 3, Fig. 1. As here shown, the cup blank is cut on a curve so as to flare upwardly from bottom to top when rolled to cup form.

After the cup blank is rolled to form, it is transferred to a forming and sealing ma- 110

chine where the bottom closure 4 is united thereto.

The closures 4 are first blanked out of a strip of suitable material and the flanges 5 simultaneously formed thereon. The next step consists in applying glue to the inner faces of said flanges, after which the side wall of the cup is bent upwardly to form the flange 2 which is folded over the flange 5 of the bottom closure. The flanges 5 and 2 are next worked relative to each other to cause them to firmly adhere to each other, after which the cup with bottom attached is tripped from the machine and the bead 3 formed thereon, if a bead is desired, such bead being rolled either inwardly or outwardly as desired.

Where paraffin is used instead of glue, the gluing step is omitted and the paraffin is applied by the same mechanism which works the flanges 5 and 2 together.

The included angle at the flange 2 is preferably of substantially the same degree as the angle of flare of the side wall 1 of the cup, but is reversed thereto, as indicated at Fig. 4. This increases the strength of the cup at its bottom by increasing the pressure of the cup wall against the flange 5 of the bottom piece 4, and the cup will not therefore open up when filled. The spacing of the flange 2 from the cup wall, moreover, affords a seat for the free edge of the flange 5 of the bottom piece 4. In other words, the flanges 2 and 5 contact with each other in a plane which is disposed out of the vertical and hence these flanges can be sealed to each other immediately after they have been coated with adhesive by bringing a downwardly exerted pressure against them to force them tightly against each other thereby making a water tight joint at the bottom of the cup. Unless relatively great pressure is applied to these flanges directly after they have been glued and joined together, the joint cannot be relied on during succeeding operations in making the cup even if the next operation is only that of gently ejecting the finished cup from the machine. A very slight movement of the flexible paper unless great pressure has been used in joining the two flanges will break the cohesion of the flanges and the cup will leak. Of course, if light pressure were used and the cups were allowed to stand in the press for a short time, it is probable that the glue would set sufficiently to permit the cup to be moved without breaking, but such a delay slows up manufacture and the use of a strong vertical pressure is therefore of great advantage. It is furthermore to be noted that while the flange 2 being reversed at the same angle to the vertical as the side wall is a smooth flange, the flange 5 of the closure

which has been crimped down from the horizontal is a somewhat crinkled or corrugated flange. By pressing this corrugated flange 5 tightly in contact with the smooth flange 2, a reinforced flange of great strength is formed. This coupled with the fact that the bottom and flange form a low truncated cone, makes a structure of very great strength, especially when reinforced by the liquid contents of the cup which surrounds the flanges.

Where the cup blank is of transparent paper stock the internal seam S or overlap of the opposite vertical edges of the cup blank may be viewed through the cup wall by the prospective drinker before he uses the cup so that if the cup has been previously used he can detect the presence of moisture in the seam S. Moreover the contents of the cup when filled may be viewed through the cup wall.

Various modifications in the construction of my receptacle, and in the manner of an apparatus for producing it, may obviously be resorted to within the limits of the appended claims.

What I therefore claim and desire to secure by Letters Patent is:—

1. In a paper vessel, an outwardly flaring side wall and a bottom, said wall and bottom having corresponding inward flanges of positive inclination bearing each on the other and united each to the other to form of the bottom and seam a substantially frustro conic element with the seam of an angularity reversed to that of the side wall and internally divergent therefrom to leave an internal channel.

2. In an inserted bottom paper cup or the like, a bottom seam composed of bottom and side wall flanges adhesively united each to the other and so disposed as to provide a V-shaped channel between the united flanges and the cup wall.

3. A paper receptacle comprising a side wall having an inwardly and upwardly disposed flange, a bottom closure of less diameter than the adjacent receptacle wall and having a flange engaged with and fitting the wall flange and cemented thereto and leaving one face of the combined flanges freely exposed to fluid pressure of the receptacle when in use.

4. A paper receptacle comprising a side wall having an inwardly and upwardly turned bottom flange, and a bottom closure member having a downwardly disposed flange interengaging with said wall flange, said flanges both being disposed at an angle to the axis of the receptacle so as to be inclined away from the side wall.

In testimony whereof I affix my signature.

WILLIAM E. BENSON.
